WEAR-RESISTANT PLATING

Gustav Sembdner, Berlin-Tempelhof, Germany

Application February 23, 1938, Serial No. 182,178
In Germany November 23, 1935

3 Claims. (Cl. 29—168)

This invention relates to metallic parts having improved wear-resistant surfaces and to methods and devices for producing wear-resistant surface layers on metallic parts, more particularly on 5 wheels for rail-vehicles.

It is the object of the invention to incorporate wear-resistant material in such a manner into the metallic parts that its structure and strength is not changed, at least not deteriorated.

10 Another object of my invention is to attach or secure the wear-resistant layer to the metallic part or support in such a manner that an undesired or inadvertent detachment or loosening is absolutely prevented, it is possible to replace or detach the wear-resistant layer with 15 simple means, if desired.

Another object of the invention is to provide simple devices and apparatus for applying the wear-resistant layers to and for removing same 20 from, their support.

A special object of the invention is to increase the duration of wheels and wheel sets for railway cars.

Still another object of the invention is to apply the wear-resistant layer by means of existing machines which require slight modification 25 only to meet their novel purpose.

With these and further objects in view, I incorporate into the surface of metallic parts which 30 are subjected to heavy stresses and wear and tear separate layers of a material having substantially higher resistance against wear and tear than the metallic part to be improved. In the practice of my invention, I force a wear-resistant plating 35 in the form of a plate or strip into recesses of the surface to be improved, by a cold or preferably hot hammering, rolling or pressing operation. The recess in the metallic part to be improved is preferably undercut or "backed off", for instance, in the form of a dovetail groove 40 or recess which is engaged by the wear-resistant plating when it is forced into the recess and de-formed.

According to a special feature of the invention, 45 the wear-resistant plates or bands are formed with a curved or arched convex cross section so that there remains clearance in the middle between the metallic part and the wear-resistant plate which clearance renders it possible to depress and flatten the wear-resistant plates, whereby their lateral edges are deformed and project and engage or intermesh with the under-cut faces.

According to a modified form of the invention, 50 one flank of the groove or recess is detachable.

so that by detaching this flank part the wear-resistant plate can be removed and replaced by a new one, without deformation.

I may incorporate the wear-resistant plates into the metallic parts or supports by cold working, but generally, I prefer to heat the wear-resistant material to facilitate its deformation without changing its inner structure. I have found that red hot temperature of the wear-resistant material is very favourable for the 5 pressing and deforming operation. Also, it is thus possible to harden the wear-resistant material by quenching it immediately following the 10 rolling, forging, hammering or pressing operation.

According to a further feature of my invention, I remove or interchange the wear-resistant plating by cutting out a portion of the wear-resistant material, for example, in the form of one or 15 more wedges or the like: To this end I may use cutting torches, grinding wheels or the like. It will be understood that the wear-resistant material on both sides of the cut can thus be moved towards the cut and disengaged from the under-cut faces for replacement by a new wear-resistant 20 plating.

The metallic part or support may be iron or 25 any other metal which is capable of forming a support for tightly securing the wear-resistant plating. The wear-resistant plating may be steel 30 which is improved or alloyed in any known manner, for instance, manganese steel containing 12-14% manganese, steel containing chromium and nickel or vanadium. Other than steel alloys may also be used, for instance, metals of the 35 hard metal group, such as tungsten, carbide or the like. Furthermore, where the wear is due to chemical attacks, platings of anti-corrosive or non-rusting material may be employed. The coefficient of thermal expansion or heat elongation 40 of the wear-resistant material should be at least approximately similar to the corresponding coefficient of the metallic support.

My invention offers special advantages in connection with wheels for rail-vehicles. As is well 45 known, the bearing or running surface and the flange of such wheels are heavily stressed and worn out very soon. My invention renders it possible to use such wheels for a much longer period of time, by incorporating wear-resistant 50 material in the flanges or tires or all over the running surface of new wheels or wheels which are to be repaired, without changing the wheel diameter.

A special advantage of my novel fastening sys- 55

tem lies in the fact that the wear-resistant material can be easily applied or incorporated and when it is worn out, can be easily removed and interchanged, by means of simple or existing 5 devices.

The invention will be better understood by reference to the following detailed description in connection with the accompanying drawings showing by way of example and schematically 10 some embodiments of the invention, viz.:

Fig. 1 is a view of a cross head bar having the invention applied thereto.

Fig. 2 is a fragmentary longitudinal section of the cross head bar shown in Fig. 1, on an enlarged scale.

Fig. 3 is a cross section on line III—III in Fig. 1, on an enlarged scale.

Fig. 4 is a cross section through a plate or strip of a material which is resistant against 20 wear and tear, for use according to the invention.

Fig. 5 is a cross section of another form of a plate.

Fig. 6 is a perspective schematical view of a 25 curved surface improved according to the invention.

Fig. 7 is a cross section of a wear-resistant plate which may be used for the purpose herein-after set forth:

Fig. 8 is an elevation, partly in section, of a 30 capstan or winch drum improved according to the invention.

Figs. 9 and 10 are fragmentary longitudinal 35 and cross sections of the rim of a rope pulley brake drum or the like, having the invention applied thereto.

Fig. 11 is a fragmentary cross section of the 40 rim or tire of a wheel for rail vehicles, provided with a wear-resistant plating according to the invention.

Fig. 12 is a fragmentary cross section showing 45 a method of inserting the wear-resistant plating.

Figs. 13 to 18 are further fragmentary cross 50 sections of the rim of a wheel for rail vehicles, having the invention applied thereto.

Fig. 19 is a cross section of a machine part on the surface of which the wear-resistant plating is fastened in a modifier manner.

Fig. 20 is a fragmentary cross section of a 55 wheel rim of a rail vehicle in which the wear-resistant surface is inserted in a similar manner as in Fig. 19.

Fig. 21 is a cross section similar to Fig. 20, 60 showing a wear-resistant surface composed of a plurality of parts.

Fig. 22 is a fragmentary plan view of a wheel as shown in Fig. 21, showing a staggered arrangement of the abutting faces or ends of the 65 wear-resistant strips.

Fig. 23 is a fragmentary cross section of a wheel rim illustrating a manner in which the wear-resistant plating can be fastened and removed.

Figs. 24 and 25 are a fragmentary cross section 70 and longitudinal section, respectively, showing a faulty manner of rolling a wear-resistant plating into the surface to be improved.

Figs. 26 and 27 are fragmentary cross section 75 and a longitudinal section of a device for removing or avoiding the defects occurring according to Figs. 24 and 25.

Fig. 28 is a schematic view of an arrangement for heating, rolling in and quenching wear-resistant bands in wheels for rail vehicles.

Fig. 29 is a side view, partly in section, of Fig. 28.

Fig. 30 is a schematic plan view, partly in section, of a rolling device.

Figs. 31 to 35 are plan and sectional views, 10 respectively, of joints similar to Fig. 22.

Fig. 36 is a section on line E—F in Fig. 35.

Figs. 37 and 38 are schematical sectional views, illustrating the removal of wear-resistant platings from their base or support.

Fig. 39 is a perspective view of an arrangement for rolling-in wear-resistant strips in railway wheels, adapted for use with an ordinary wheel set lathe.

Fig. 40 is a side elevation of the arrangement 15 shown in Fig. 39.

Fig. 41 is a front elevation of the same arrangement.

Fig. 42 is an elevation of a detail of the machine shown in Figs. 39 to 41.

Fig. 43 is a plan view of the parts shown in Fig. 42.

It will be understood that the principle according to this invention can be applied wherever it is possible to provide on parts or members subject to wear and tear due to friction, shocks or the like, interchangeable surface layers, irrespective of whether the parts or members to be protected have prismatic surfaces, as for instance, grinding surfaces or sliding surfaces, or curved or profiled surfaces, as for instance wheels for rail vehicles, brake drums, pulleys, rollers etc. The wear-resistant platings may be of any material which is entirely different from the basic or support material provided only that the wear-resistant material is capable of being deformed by pressing, rolling, hammering, forging or the like.

Referring now to the drawing in greater detail, and first to Figs. 1 and 2, it will be seen 40 that a cross head slide plate of a locomotive has been illustrated. Inserted into the slide plate body 1 of soft steel are two slide surfaces 2 and 3 of a material offering a higher resistance against wear. To this end grooves or recesses 45 of the type shown at 4 or 5 in Fig. 3, having undercut flanks or dove-tailed cross sections, are milled or cut into the slide body 1. Embodied in these grooves are wear-resistant strips or plates 6 or 7, respectively, of a suitable cross 50 section so as to form the desired surface in connection with the grooved surface. These strips are held in the grooves merely by engagement in the undercut faces of the grooves, without welding, soldering or otherwise heating the slide 55 body 1. The strips or plates 6, 7 are so shaped that the dovetail flanks are formed only by forcing the wear-resistant material into the grooves or recesses 4 or 5, under action of pressure. The required shape of the strips 6 and 7 will be seen 60 from Figs. 3, 4 and 5. The platings 6 or 7 may be secured against longitudinal displacement by thickened portions at the groove ends, as indicated at 8 in Fig. 2. Advantageously, a strip having an arched, convex section is urged into 65 the groove in red hot condition, and flattened. Immediately after the strips 6, 7 have been inserted into the grooves 4 and 5, the wear-resistant material may be hardened, for instance, by quenching it by means of water, air or any 70 other suitable hardening or quenching agent. The undercut grooves will prevent warping or other deformation of the wear-resistant strip. Where the wear-resistant material is applied in the form of the strip 6, a shrinking action will 75

additionally occur which aids in obtaining a reliable joint. The surface layers thus tightly connected with the body 4 may be ground or otherwise machined in the usual manner. 5 When the wear-resistant material is completely worn out, after it has been ground repeatedly, the wear-resistant material may be removed by cutting it into two parts lengthwise in suitable manner, for example by a cutting torch, without impairing the grooves of the slide body 4, and replaced by new wear-resistant platings, in the manner hereinbefore described.

The cross section of the strips 6 or 7 may be produced in a rolling operation, but it will be understood that small quantities of the wear-resistant strips may be produced in any other suitable manner, for instance, by forging the material in a swage or by shaving. A plurality of wear-resistant plates of a similar cross section 20 may be arranged side by side, as shown at 9 in Fig. 6. The cross section of the platings according to Fig. 6 before the pressing operation is shown in Fig. 7, indicating an arched convex form of the cross section. As will be seen from 25 Fig. 6, concave and convex surfaces may be provided with platings having the same initial cross section.

Circular surfaces of any form may also be plated with wear-resistant material. For instance, Fig. 8 shows a capstan drum having wear-resistant working surfaces incorporated in ordinary material. As shown in the right hand half of Fig. 8, a strip 10 of convex cross section is put on the surface to be plated which is recessed as 30 shown and the strip is now depressed or pressed on, preferably by means of rollers, in red hot condition, so as to assume the shape shown in the left hand half of Fig. 8 and to lie flush with the surface of the capstan drum.

40 Referring now to Figs. 9 and 10, it will be seen that the rim or running surface of a wheel, brake drum or pulley is plated with two strips 11 parallelly arranged in said rim. The right hand strip in Fig. 10 indicates the initial cross section of the strip before it is deformed while on the left hand side of Fig. 10 the strip 11 is shown pressed or rolled into the dovetail recesses of the groove in the rim.

Various embodiments of wheels for rail vehicles, as used in railway cars or tramway cars, 50 are shown in Figs. 11 to 18 and 20 to 23. As is well known, the running surfaces of such wheels are subjected to many different stresses and have to be corrected as to their cross section at regular intervals. Now, I provide those portions of the cross section of the rim which are mostly stressed and worn out with a plating or insert of a material offering extremely high resistance against these stresses and wear and tear, whereby the 55 wheels may be used for a much longer time until correction and machining is again required. Moreover, when the cross section of the rim is worn down to the admissible limit, my novel system of fastening the wear-resistant plating to the wheel surface renders it possible to interchange or replace the wear-resistant plating in a simple manner, as will be hereinafter described.

Figs. 11 and 12 show the cross section of a tire 60 of a railway wheel having its mostly stressed portion at 12. In order to protect the wheel against wear, I cut a groove or recess into said portion 12 having undercut flanks 13 and 14. Now a strip 15 of a material offering a very high 65 resistance against wear is hammered, forged,

pressed or rolled into said groove, whereby it is securely and intimately connected with the rim. The wheel may now be used until the admissible lower limit of the cross section of the rim is reached. In this case the wear-resistant strip 5 15 is usually also worn out to such an extent that a new wear-resistant strip or insert has to be applied. To this end, the wheel rim is turned down to the smaller standard cross section 16. It is not necessary in this turning operation to 10 turn the whole rim down to the lowest point of the worn flank 12 of the wheel flange, since a groove 17 having undercut flanks 18, 19, is turned into this flank, into which a strip similar to the strip 15 in Fig. 11 is forced. As shown in Fig. 12, 15 the strip is at first 8-shaped so that it can be inserted into the groove 17. After the strip 15 has been inserted, it is stretched in the groove, by means of a press punch or roller 18', in the manner hereinbefore described. It will be understood that instead of a narrow groove and strip as shown in Figs. 11 and 12, a wider groove and strip may be used, as indicated by the dotted line 20 in Fig. 12, so as to cover practically the 25 whole running surface of the wheel.

Further manners of fastening the wear-resistant plating on the wheel rim are shown in Figs. 13 and 14, illustrating two dovetail grooves 21, 21' and 22, 22' into which a suitably curved and arched strip 43 is inserted, the initial shape of 30 which is shown in Fig. 13. This strip 43 is rolled and deformed as shown in Fig. 14 to form a smooth running surface together with the wheel rim.

I contemplate to provide also the flanges of the 35 wheels with a wear-resistant plating, for example, in the manner shown in Figs. 15 and 16 or 17 and 18, respectively. In this case, the wear-resistant plating is preferably additionally secured to the wheel rim at the back of the flange 40 at 23, by means of a dovetail or undercut groove. Figs. 15 and 17 show the wear-resistant strip in its initial cross sectional shape, while Figs. 16 and 18 show the same strip finished and deformed to be smooth and fast in the groove of 45 the wheel rim.

According to a further feature of the invention I may provide one of the flanks of the dovetail groove to be detachable from the metallic support. This renders it possible to insert the wear-resistant plating without deformation thereof and to remove the wear-resistant plating without cutting it into pieces. Embodiments of this modification are shown in Figs. 19 to 21. Fig. 19 is a cross section of a machine part 24, for instance, a slide plate provided with wear-resistant surfaces 25 and 26. The body 24 consists of a soft material offering a small resistance only against wear and tear and is provided with platings 27, 28, the undersides of which have undercut flanks 29, 29', preferably in the form of a dovetail cross section. The dovetail flanks 29 are engaged into the undercut flanks 30 of the body 24 and secured in this position by a closure member 24' engaged in the opposite recesses 29' 55 of the members 27 and 28, by means of corresponding projections 30', and attached to the body 24 by means of screws 31 or like means. It will be understood that the platings 27, 28 may be hardened and/or ground after or prior to 60 being secured to the body 24.

A similar fastening is shown in Figs. 20 and 21, showing in Fig. 20 a wheel rim 36 provided with a ring 38 of wear-resistant material interlocked in the direction of the arrow in a recess 34 of 70 75

the wheel rim and secured in position by means of a closure ring 32 fastened to the wheel rim 36 by means of screws 31 and engaging the ring 35 by a projection 33. By way of alternative, the closure ring 32 may be fastened on the rim 36 by putting it on in a heated condition and allowing it to shrink so as to be held on the rim 36 by adhesion. According to Fig. 21 the ring of wear-resistant material 35 is composed of three component rings 35', 35'', 35''', the arrangement being for the rest the same as in Fig. 20. It will be understood that this construction renders it possible to interchange or replace worn out strips 35 or single portions 35', 35'', 35''' by merely detaching the closure member 32. The wear-resistant rings or ring portions may then be readily stripped off from the wheel rim and replaced by new wear-resistant rings.

Another modification is shown in Fig. 23, showing a wheel rim 36 which is provided with an annular strip 37 engaging the open groove 39 and secured in its position by a further annular strip 38 which is rolled in and engages a dovetail projection 36' of the rim 36, thus locking the strip 37 in its position. It will be understood that the two parts of the wear-resistant strip thus applied can be removed by a single annular cut of a cutting torch applied at 40 which cut does not require to go through to the bottom of the groove 39 and therefore cannot injure the same. The two parts of the strip 38 thus obtained can now be readily removed to permit removal of the strip 37.

Where a plurality of parts of wear-resistant material, for example several parallelly arranged strips are used for plating the surface of a wheel, as indicated in Fig. 21, the different joints 41', 41'', 41''' of the strips are staggered as shown in Fig. 22 so that the joints are protected against excessive wear and tear. Further possibilities of arranging a joint will be hereinafter described.

Generally, there is a very small clearance only between the groove or recess and the wear-resistant material inserted in the recess; therefore, water or other aggressive substances will not usually be permitted to enter into the groove. Where it is intended to protect the groove additionally against corrosion, the surface of the groove and/or the inwardly directed surface of the wear-resistant material may be provided with an anti-corrosive or non-rusting coating which may be very thin, since it is protected against mechanical injuries by the wear-resistant strip. In Fig. 13 a coating 42 of anti-corrosive material has been indicated on the surface of the recess which coating may be applied by a galvanic process, by a spreading process or by a metal spraying process. A similar coating 43 is shown on the inner face of the wear-resistant strip in Fig. 13. Where the strip is not heated in the attaching operation, this coating may be applied in the same manner as the coating 42; where the strip is attached in hot condition, a coating of a refractory or fire-proof material has to be applied.

The provision of a protective coating between the wear-resistant material and its support is an important feature of my invention. More particularly this coating renders it possible to ensure a reliable and durable metallic contact between the wear-resistant material and its support which contact is important, for instance, in case of wheels for rail-vehicles or slide contacts intended to transmit electric current from the rail to the wheel or slide contact. Moreover, I have found that the said protective coating forms a bar for the flame of a cutting torch so that the

surface of the groove is not impaired or injured by the cutting flame.

In some instances when the wear-resistant strip is rolled into the recess of its support with a corresponding increase in width, the portion of the strip shortly prior to the rolling station tends also to become wider, whereby difficulties arise in inserting the strip into the recess. This is shown schematically in Fig. 25 and in Fig. 24 which is a section on line A-B in Fig. 25. 44 is the band or strip to be inserted which is arched as at 45. The support is provided with a dovetail groove 46 into which the wear-resistant strip is forced by means of a roller 47. Now, I have found that the strip 44 tends to flatten already prior to the point where it is depressed by the roller 47, whereby its exterior edges 48, 48' overlie the groove, leaving a clearance 49 between strip and groove. In order to avoid this defect, I guide the strip 44 through a guiding device, as shown in Figs. 26 and 27 which is adapted to the width of the strip and prevents flattening of the strip outside the groove, and ensures at the same time a smooth rolling operation. As will be seen in Figs. 26 and 27, guiding members 50, 50', 50'', 50''' are provided in front of the roller 47 for guiding the strip. It will be understood that the guiding members 50, 50', 50'', 50''' may be constructed in the form of a single unitary device.

Figs. 28 and 29 illustrate by way of example and schematically the rolling operation applied to a rail wheel of the kind shown in Figs. 11 and 12. The wear-resistant strip of convex shape is guided through a heating device 52, for instance, a muffle furnace and pressed into the groove 54 of the wheel rim by means of the roller 53, the cross section of which corresponds to the flank of the flange of the wheel. The finished strip 51 can be hardened by means of a quenching device 55 in the form of a water spraying nozzle or the like. A modified form of the roller is shown in Fig. 30, illustrating a roller 56 which is provided to roll a wear-resistant strip 57 into the groove 58 of a rail wheel 59, so as to improve the running surface and the flank thereof. It will be understood that a roller of the shape shown in Fig. 30 may also be used in the device shown in Fig. 28 and 29, instead of the roller 53. Various forms of joints of wear-resistant strips are shown in Figs. 31-36. According to Figs. 31-32, the two abutting strip ends overlap each other at 60, 61, leaving gaps 62, 63. The joint shown in Figs. 33 and 34 is connected by a welded seam 64. Figs. 35 and 36 show a staggered oblique joint. It will be understood that the construction and form of the joint depends on the stress to which the respective metallic part is subjected in operation.

In order to remove platings of material from their metallic supports, the plating may be cut into pieces, as shown in Fig. 37, by means of a cutting torch 65, so as to form a wedge-shaped middle portion 67 separated from the lateral portions by cuts 66. According to Fig. 38, the middle portion 67 is then taken off or raised and the side 68 and 68' are moved to the center so that they can be easily lifted out of the groove. Where the cut is made very wide, a single cut will be sufficient in many instances, to permit removal of the wear-resistant portions. With some of the fastening constructions, as for instance, that shown in Fig. 23, only a separating cut 40 is required. The cut may be made by any suitable cutting tool other than a cutting torch, for in-

stance, by means of grinding wheels, cutting chisels, saws or the like.

It will be understood that my novel principle can be applied not only to existing wheels for rail vehicles having separate tires, as for instance, illustrated in Fig. 29, but the invention especially permits of the manufacture of wheels having no tire at all, but having simply a grooved rim into which the wear-resistant strip is rolled, as indicated in Fig. 23. In this case the wear-resistant strip can be removed from the wheel and replaced by a new one when it is worn out.

Generally, any suitable rolling machine or apparatus may be used to apply the wear-resistant material to its support, but in case of round metallic parts, more particularly wheels, I prefer to employ ordinary wheel set lathes reconstructed or modified to meet the purpose in question. By way of example, Figs. 39 to 43 show a device of this kind, comprising a face plate or disc 71 of a wheel set lathe and a base plate 72 for the slides. The wheel set 73, one wheel of which 74 has been shown only, for the sake of clarity, is inserted or chucked in the usual manner, preferably in such a way that the axle stub 75 of the wheel set rotates on the center 76 of the face plate 71 while the wheel set is rotated in usual manner, for instance, by drivers from the opposite face plate which is not shown in the drawings. The two slides are removed from the plate 72 and replaced by a device 77 (Fig. 40) by which the strip 78 can be rolled into the groove 79 of the wheel. The strip 78 passes through a guiding device 80 which, as already mentioned, may receive the heating device for the strip at the same time.

The device 77 comprises a roller 81 which has a cross section corresponding to the profile or cross section of the wheel. This roller 81 is guided in a fork-shaped frame 82 terminating in a rod 83 (Figs. 42 and 43) which is adjustable in the anchor plate 85 by means of a screwing device 84, so that the roller 81 is supported by this anchor plate 85. The plate 85 in turn is relieved from the forces thus acting upon it by brackets 87, 87' (Fig. 41) surrounding the axle 78 of the wheel set and the emergency running surface 86 or the axle stub 75 of the wheel 74, and connected by tension rods 88, 88' to the anchor plate. The plate 85 is thus quasi "suspended" from the axle 80 of the wheel. Rollers 89 are provided in the bracket 87 and rollers or slide bodies are provided in the bracket 87'. In this manner the roller 81 can be adjusted to exert the desired pressure by means of the screwing device 84 which advantageously is connected with the rod 83 by a ball and socket joint.

The roller 81 due to the different thicknesses of the flanges or tires 90 will sometimes have a lateral clearance with respect to the said tire or flange 90 which should be advantageously limited or entirely eliminated. To this end I provide a circular disc 91, the shaft 92 of which is inclined with respect to the shaft of the roller 81 and the surface 93 of which is wedge-shaped so as to engage the space between the tire 90 and the roller flange 81'. It will be understood that the play or clearance between the tire 90 and the roller 81 can be easily changed or eliminated by moving or pressing the disc 91 more or less into this inter-space, by means of the screwing device 94.

The disc 91 is supported on the bracket 95 which may be secured to the fork 82 by means of screws. According to another modification of the invention the clearance between the tire and the roller may be eliminated by providing the

roller 81 with interchangeable or adjustable lateral flanges 81', as shown in Fig. 43. Also the clearance between the roller 81 and the tire may be eliminated by means of lateral pressure rollers (not shown) or the like.

Provided at 96 between the guide plate 80 and the flange 90 in Figs. 39 and 42 is the guiding device for the strip 78 which has been hereinbefore described with reference to Figs. 26 and 27; the shape of this device is adapted to the profile or cross section of the groove and strip.

It will be understood that the machine operates in such a manner that the wheel set 73 rotates in a counter-clockwise direction, whereby the strip 78 is pressed into a groove of the wheel 74 under action of the pressure exerted by the roller 81. The groove portion of the wheel and the portion of the strip already rolled-in pass through a container 97 filled with a suitable quenching agent, as for instance, water or oil or a salt solution. Alternatively, a squirting device may be provided as in Fig. 28.

While I have herein shown and described certain preferred embodiments of my invention, I wish it to be understood that I do not confine myself to all the precise details herein set forth by way of illustration, as modification and variation may be made without departing from the spirit of the invention or exceeding the scope of the appended claims.

I claim:

1. In a method of removing from a metallic support a wear-resistant layer engaged in undercut recesses of said support, the steps which comprise cutting out a portion of the wear-resistant material coextensive with the undercut recesses so that the wear-resistant layer is split up in two parts, and withdrawing the two wear-resistant parts from the undercuts so that they can be taken off from the support.

2. A wheel including a rim portion having a circumferential groove with undercut retaining means in triplicate in and coextensive with said groove, and a pair of wear resistant elements mounted in said groove, a first of said elements having preformed portions thereof engaged with a pair of said retaining means and having one edge thereof comprising an undercut retaining means for the other of said elements, said other element having preformed portions thereof engaged with the third of the first said retaining means and the last said retaining means, said elements consisting of strip members having in combination substantially the same cross-sectional shape as said groove, the ends of the respective strip members arranged to adjoin each other in said groove in circumferentially displaced positions.

3. A wheel including a rim portion having a circumferential groove with undercut side walls, one of said side walls being integral with said rim portion, a retaining element removably secured to said rim portion and shaped to provide the other of the undercut side walls of said groove, a wear resistant element mounted in said groove with preformed portions of said element engaged with complementary portions of said groove, said element consisting of a strip of substantially the same cross-sectional shape as said groove with the ends of said strip arranged to adjoin each other in said groove to provide a smooth running surface for said wheel, said strip element being removable and replaceable upon removal of said retaining element.
